UNITED STATES PATENT OFFICE.

AMEDEO DEL ROSSO, OF CHICAGO, ILLINOIS, ASSIGNOR OF ONE-HALF TO EMIL DEL
ROSSO, OF CHICAGO, ILLINOIS.

PADLOCK.

Application filed May 19, 1927. Serial No. 192,573.

This invention relates to safety padlocks for use wherever applicable; and it consists of a padlock provided with a combination device and a key both of which are necessary to effect the opening of the lock, said padlock being constructed as hereinafter fully described and claimed.

In the drawings, Figure 1 is a side view of the padlock with a portion of the case removed, and showing the hasp locked. Fig. 2 is a longitudinal section through the case showing the hasp unlocked and raised. Fig. 3 is a sectional plan view through the case, taken on the line 3-3 in Fig. 1. Fig. 4 is a cross-section through the case, taken on the line 4-4 in Fig. 2. Fig. 5 is a cross-section through the case, taken on the line 5-5 in Fig. 2. Fig. 6 is a cross-section through the case, taken on the line 6-6 in Fig. 2. Fig. 7 is a side view of the key. Fig. 8 is an end view of the key.

The lock is provided with a case 10 which is preferably cylindrical. Heads 12 and 14 are secured in the respective ends of the case, and the head 14 is provided with a key hole 15 on the axis of the case, and this key hole has any suitable pivoted cover.

The hasp 9 is hook-shaped, and one end portion 16 is a straight spindle which slides longitudinally and rotates in guide holes 17 in the sides of the case crosswise of its axis. The other end portion 18 of the hasp is a straight rod arranged parallel to the spindle 16, and is slidable in a hole 19 in one side of the case crosswise of its axis, when the hasp is rotated to the position shown. The end portion of the spindle 16 is provided with a stop 20 which comes in contact with the case when the hasp is slid so that the rod 18 is clear of the hole 19.

A spring chamber 21 is secured to the spindle 16 on the other side of the case from the stop 20, and a releasing spring 22 is inclosed in this chamber, and operates automatically to slide the hasp to the unlocked position, as shown in Fig. 2. A disk 24 is secured in the case between the spindle 16 and the head 12. A short shaft 25 is journaled in the disk 24 and head 12, on the axis of the case, and a combination disk 26 is secured on one end portion of this shaft

outside the case. The combination disk 26 is preferably a cap which fits over the head 12, and it is provided with suitable graduations which are numbered. The case is provided with a suitable mark or pointer for the graduations, but the disk and case may have any other suitable markings such as used on combination locks.

A disk 28 is secured in the case on the other side of the spindle 16 from the disk 24, and an intermediate disk 29 is secured in the case substantially midway between the disk 28 and the key hole head 14. A locking bolt 30 is arranged on the axis of the case, and is slidable in holes in the disks 28 and 29. A locking spring 31 encircles the locking bolt 30, and is arranged between the disk 29 and a pin or projection 32 on the locking bolt, and this spring projects the locking bolt into a hole 33 in the spindle 16, when the said spindle is pushed to the locked position by hand against the pressure of the releasing spring 22. The locking bolt 30 has an operating pin or projection 34 which projects crosswise of it, and is arranged between the disk 29 and the key hole head 14 at a predetermined distance from the key hole.

The locking bolt 30 is prevented from rotating by any suitable means, and 35 are guide pins arranged in pairs parallel to each other between the disk 29 and the key hole head 14. A pin 36 projects crosswise of the locking bolt, and projects between the pairs of guide pins, and prevents the locking bolt from rotating, but permits it to slide longitudinally.

A locking shaft 38 is journaled in the heads and disks, to one side of the hasp spindle 16, and parallel to the locking bolt. This shaft 38 is rotated from the shaft 25 of the combination disk 26 by means of toothed wheels 39 which mesh into each other and are secured on the said shafts. A locking disk 40 is secured on the locking shaft 38 adjacent to the key hole head 14, and has a notch 41 in its periphery, and has also pins 42 which project from one side of it at its periphery. The periphery of the locking disk and its pins 42 are arranged closely adjacent to the locking bolt.

The key 45 has a tubular end portion 46, and hooks 47 on the end thereof, and the tubular end portion is slidable through the key hole and over the free end portion of the locking bolt. When the notch 41 of the locking disk is opposite the locking bolt, the key can be inserted and slid through the notch, and turned a little around, so that its hooks engage with the operating pin 34. 10 The locking bolt can then be retracted by the key, so as to free the spindle of the hasp, and the hasp is then slid by its releasing spring 22 to the position shown in Fig. 2. The hasp can then be rotated by hand to open it to the desired extent. The key cannot be inserted to its full extent unless the notch is opposite the locking bolt, because the end of the key strikes the locking disk.

The notch 41 is placed opposite the locking bolt by turning the combination disk to indicate the predetermined combination, and the notch cannot be so placed by anyone not knowing that combination. The key is made to fit the key hole and the locking bolt, and the hasp cannot be unlocked except by a person having the correct combination and the proper key.

The pins 42 on the locking disk prevent the locking disk from being completely rotated when the key is partially inserted in an attempt to find the correct combination by feeling for the notch with the end of the key pressed against the locking disk. The pins 42 are arranged to strike the key, and prevent the locking disk from being rotated sufficiently to place the notch opposite the locking bolt, so as to permit the key to be inserted to its full extent to engage with the operating pin.

40 What I claim is:

1. In a padlock, a case, a hasp having a spindle which is slidable and rotatable in holes in the sides of the case and having an end portion which interlocks with the case, a locking bolt mounted on the axis of the case and normally engaging with the said spindle, said locking bolt being provided with a projection for operating it, a locking shaft journaled in the case parallel to the locking bolt, a locking disk secured on the locking shaft with its periphery adjacent to the locking bolt and having a notch adapted to be placed opposite the locking bolt to permit the insertion of a key to operate the locking bolt, and a combination device arranged outside the case and operatively connected with the locking shaft.

2. A padlock as set forth in claim 1, the said combination device being provided with a combination disk journaled on the axis of the case, and having also a shaft and intermeshing toothed wheels which operatively connect the combination disk with the said locking shaft.

65 3. A padlock as set forth in claim 1, the

said locking bolt being provided with a projection, and the said case having an abutment secured inside it, and a spring encircling the locking bolt and arranged between the said projection and abutment and operating to project the locking bolt into engagement with the hasp spindle when the hasp is placed in the locked position.

4. A padlock as set forth in claim 1, the said locking disk being provided with lateral projections which strike the key and prevent the complete rotation of the locking disk in an attempt to find the correct combination.

5. In a padlock, a case, a head closing one end of the case, a hasp having a spindle which is slidable and rotatable in holes in the sides of the case and having an end portion which interlocks with the case, a head closing the other end of the case and provided with a key hole, disks secured in the case between its heads, a locking bolt for the said spindle slid able in the said disks on the axis of the case and provided with a projection for operating it, a locking shaft journaled in the said heads and disks parallel to the locking bolt, a locking disk secured on the locking shaft with its periphery adjacent to the locking bolt and having a notch adapted to be placed opposite the locking bolt to permit the insertion of a key through the key hole to operate the locking bolt, and a combination device arranged outside the case and operatively connected with the locking shaft.

6. A padlock as set forth in claim 5, and having also a disk secured in the case adjacent to the hasp spindle and between it and the first said head, a short shaft journaled in the said head and disk, and intermeshing toothed wheels connecting the short shaft with the said locking shaft, the said combination device having a combination disk which is secured on the said short shaft outside the case.

7. A padlock as set forth in claim 5, and having also means which prevent the slid able locking bolt from rotating in the said disks.

8. A padlock as set forth in claim 5, the said locking disk being arranged in the case between the key hole head and the operating projection of the locking bolt, and the said disks being secured inside the case between the hasp spindle and the locking end portion of the hasp.

9. In a padlock, a case, a hasp for engaging with the case and having a rotatable spindle which is slidable longitudinally in guides crosswise of the case, a locking bolt for the said spindle mounted in the case, means for operating the locking bolt to lock and unlock the hasp spindle, a stop on one end portion of the spindle which bears on one side of the case and limits the movement of the spindle to the unlocked position of the hasp, a chamber secured on the other end portion of the spindle and forming a stop which bears on the other side of the case and which operates

to position the spindle in its locked position, and a spring inclosed in the said chamber and operating to unlock the hasp from the case automatically when released from the locking bolt.

10. In a padlock, a case, a hasp for engaging with the case and having a rotatable spindle which is slidable longitudinally in guides crosswise of the case, a locking bolt 10 slidable longitudinally of the case and operating to lock the hasp spindle, a chamber se-

cured on the hasp spindle and forming a stop which bears on one side of the case and operates to position the hasp spindle in its locked position, and a spring inclosed in the 15 said chamber and operating to unlock the hasp from the case when its spindle is released from the locking bolt.

In testimony whereof I have affixed my signature.

AMEDEO DEL ROSSO.
